UNITED STATES PATENT OFFICE

2,572,680

RUNNING SHOE

Floyd C. Treat, Barrington, Ill., assignor to The
Athletic Shoe Company, Chicago, Ill., a corpora-
tion of Illinois

Application August 16, 1947, Serial No. 768,969

2 Claims. (Cl. 36—2.5)

1

My invention relates to running shoes especially adapted for an outdoor track, and is also applicable to other games and sports where running speed and agility are of prime consideration, as in certain positions in football. My invention is particularly concerned with a cleated or spiked shoe having certain improvements in regard to the number and position of the cleats or spikes of such shoes.

I am especially concerned, in this invention, with the shoe requirements for sprinting, whether it be on a cinder track or playing field. In such activity a runner, as he moves over the ground, customarily supports his weight almost entirely on his toes, propelling his body by pulling himself forwardly at each pace or step. I have made a close study of this body action over a period of many years, as a result of which I have reached the conclusion that it has been customary, in previously known shoes, to provide an excessive number of spikes and to position them incorrectly and not according to applicable scientific principles. After giving long study to this problem, I have evolved an arrangement which (1) reduces the weight of the shoe, (2) adds to its flexibility, (3) provides improved traction at precisely the required points relative to the foot, and (4) provides the necessary support to the bones of the foot most involved in running.

In accordance with my invention, I provide a shoe with four cleats, each positioned where it will do the most good rather than placed haphazardly or for reasons of symmetry, as in the shoes previously known, which commonly employed six cleats. By eliminating surplus cleats, I achieve greater flexibility, better traction, reduction of weight and other advantages.

Objects of my invention, therefore, are to provide a shoe which will have the important advantages and avoid the prior art disadvantages outlined above. It should be understood that, although I use a track shoe as a preferred illustration of my invention, this should be considered merely as an example and not as limiting, and the word "cleat" as used herein should be interpreted as a general term indicating any suitable ground engaging element.

Referring now to the drawings illustrating a preferred embodiment of my invention:

Figure 1 is a plan view of the sole of a shoe embodying my invention, certain bones of the foot being dotted in, as shown in an actual X-ray photograph, to show the relation of the cleats to the bones, and

2

Figure 2 is a side elevation of the same, again with a dotted showing of appropriate bones.

The numeral 10 indicates in general a track shoe embodying my invention, having an upper 12, a sole 13, and a sole tap 14, the latter being reinforced, if desired, by the interposition of a spring steel plate (not shown) in the sole. It should be noted that the tap 14 terminates, as at 16, on a line well in advance of the arch or 10 instep of the foot and immediately behind the ball of the foot, as seen best in Figure 2; also, that the toe portion 18 of the shoe is preferably square, although it may be rounded if desired. At any rate, it is broad enough to comfortably 15 accommodate the toes.

Coming now to the cleats (which, in the track shoes illustrated, are in the form of metal spikes), I provide four for each shoe and position them as follows:

20 Cleat 20 is positioned substantially under the first joint or distal bone of the first phalange of the great toe, approximately midway of its length. Cleat 22 is placed approximately under the second and third toes of phalanges, and 25 approximately on a line with cleat 20 transversely of the axis of the foot. It should be understood that the exact position of cleat 22 is not critical, its purpose being primarily to provide a balance for the foot against cleat 20. The 30 position of the latter, however, has been selected in order to take full tractive advantage of the superior strength of the great toe and bones connected therewith.

Cleats 24 and 25 are positioned substantially 35 under the ball of the foot. Thus, cleat 24 is approximately under the second pivot of the great toe, i. e., at the joint between the proximal and metatarsal bones, again to take maximum advantage of the great driving power of these

40 powerful bones of the foot, and is roughly rearward of cleat 20 relative to the axis of the foot. Cleat 25 is placed approximately under the corresponding pivot of the third phalange, being spaced from cleat 24 on a line transverse of the 45 axis of the foot. Thus, these two cleats, positioned under the flexing portion of the ball of the foot and widely spaced thereunder, provide along with the cleats 20 and 22 maximum traction where the foot of a sprinter meets the 50 ground.

It should be noted that by cutting off the tap of my shoe immediately behind the ball of the foot I provide all the support needed for the cleats and, at the same time, reduce weight and 55 add greatly to the flexibility of the shoe. The

shoe rearwardly of the top holds the foot as in a glove providing firm but yielding support to the bones which thus are permitted the utmost flexibility in running. This results in enhanced comfort and speed.

The broad toe of the shoe permits complete freedom of action of the toes of the foot.

The advantages of my invention and superior features thereof can best be appreciated by comparison with a standard or orthodox track shoe. It will be seen that six cleats are commonly provided; and in order to accommodate them, a tap is used which extends well behind the ball of the foot and across the instep, greatly reducing the flexibility of the shoe. To accommodate the two forward cleats, the shoe is pointed at the toe and the position of the bones, especially the bent distal and proximal bones of the great toe, clearly show the cramping effect of this construction. None of the cleats is positioned where it will achieve maximum tractive effect, and the excessive number of cleats and size of the tap add an undue burden of weight to be carried by the runner and reduce flexibility and restrict the movement of his foot. Further, each unnecessary ground penetrative element reduces his speed by adding useless work to every step.

I am familiar with Shapiro Patent No. 2,095,766, issued October 12, 1937, and Walther Patent No. 2,080,680, issued May 18, 1937, but do not consider that they anticipate my invention here described and claimed.

Various modifications will doubtless suggest themselves to those skilled in the art, and hence I do not wish to be restricted to the forms shown and uses mentioned, except to the extent indicated in the appended claims.

I claim:

1. A running shoe having a sole and an upper, a sole tap terminating in a straight line positioned a substantial distance forward of the ball line, and four cleats extending through the sole tap and providing the sole traction means for the shoe, one of said cleats being positioned approximately under the distal bone of the great toe, another cleat for balancing said distal cleat being disposed approximately on a line with the latter transversely of the axis of the foot, and a pair of spaced cleats being disposed adjacent the rear extremity of said tap and substantially under the base joints of the toes whereby, when said shoe is used for running or sprinting, all four of said cleats will penetrate the ground throughout the major portion of their length.

2. A combination as defined in claim 1, wherein one of said rearwardly disposed cleats is disposed substantially under the base joint under the great toe and the other of said rear cleats is disposed substantially under the base joint of the fourth toe.

FLOYD C. TREAT.
